UNITED STATES PATENT OFFICE

112,414

DESIGN FOR DRAPE FOR CHAPEL TENT

Cecil M. Wickstrum, Omaha, Nebr.

Application April 2, 1938, Serial No. 76,236

Term of patent 3½ years

To all whom it may concern:

Be it known that I, Cecil M. Wickstrum, a citizen of the United States, residing at Omaha, in the county of Douglas and State of Nebraska, have invented a new, original, and ornamental Design for Drape for Chapel Tent, of which the following is a specification, reference being had to the accompanying drawing, forming part thereof.

I claim:

The ornamental design for drape for chapel tent, as shown.

CECIL M. WICKSTRUM.
